CLAIM

The ornamental design for a grille guard bracket, as shown and described.

DESCRIPTION

FIG. 1 is a perspective view of the grille guard bracket of the present invention,

FIG. 2 is a side view of the grille guard bracket illustrated in FIG. 1, the left and rights sides of the grille guard assembly being mirror images.

FIG. 3 is a front view of the grille guard bracket illustrated in FIG. 1,

FIG. 4 is a rear view of the grille guard bracket, illustrated in FIG. 1,

FIG. 5 is a top view of the grille guard bracket illustrated in FIG. 1,

FIG. 6 is a bottom view of the grille guard bracket illustrated in FIG. 1,

FIG. 7 is an environmental perspective view of the grille guard bracket illustrated in FIGS. 1-6 particularly illustrating the grille guard bracket being included within an assembly for coupling a grille guard to a portion of a work vehicle according the present invention,

FIG. 8 is a side view of the grille guard bracket illustrated in FIG. 7, the left and rights sides of the grille guard bracket being mirror images,

FIG. 9 is a front view of the grille guard bracket illustrated in FIG. 7,

FIG. 10 is a rear view of the grille guard bracket illustrated in FIG. 7,

FIG. 11 is a top view of the grille guard bracket illustrated in FIG. 7,

FIG. 12 is a bottom view of the grille guard bracket illustrated in FIG. 7,

FIG. 13 is yet another environmental perspective view of the grille guard bracket illustrated in FIGS. 1-6, particularly illustrating the grille guard bracket being included within an assembly for coupling a grille guard to a portion of a work vehicle according to another aspect of the present invention,

FIG. 14 is a side view of the grille guard bracket illustrated in FIG. 13, the left and right aides of the grille guard bracket assembly being mirror images,

FIG. 15 is a front view of the grille guard bracket illustrated in FIG. 13,

FIG. 16 is a rear view of the grille guard bracket illustrated in FIG. 13,

FIG. 17 is a top view of the grille guard bracket illustrated in FIG. 13.

FIG. 18 is a bottom view of the grille guard bracket illustrated in FIG. 13; and,

FIG. 19 is a further environmental perspective view of the grille guard bracket illustrated in FIG. 7, particularly illustrating the assembly shown in FIG. 7 installed onto the front of a work vehicle, such as an agricultural tractor.

The broken lines of the grille, other assembly components and work vehicle represent environment and form no part of the claimed design. The broken lines of the bracket represent boundaries and form no part of the claimed design.
